LEWIS C. MYERS, OF BROOKLYN, NEW YORK, ASSIGNOR TO ROYAL TYPEWRITER COMPANY, INC., OF NEW YORK, N. Y., A CORPORATION OF NEW YORK.

STENCIL-MAKING DEVICE FOR TYPE-WRITING MACHINES.

1,243,858.

Specification of Letters Patent. Patented Oct. 23, 1917.

Application filed May 3, 1915. Serial No. 25,408.

To all whom it may concern:

Be it known that I, LEWIS C. MYERS, a citizen of the United States of America, residing in the borough of Brooklyn, county 5 of Kings, and State of New York, have invented a certain new and useful Stencil-Making Device for Type-Writing Machines, of which the following is a specification.

The stencil making device of this invention embodies a structure adapted to hold the stencil flat while being printed on a visible printing typewriting machine by the ordinary machine type, and to move it, for line spacing, etc., in a tangential direction 15 relative to the rotary bed or platen which receives the impact of the type on the stencil. It also embodies means for feeding and controlling an ink ribbon arranged to cover the part of the platen, behind the 20 stencil.

In the drawings which fully illustrate this invention:

Figure 1 is a front elevation of the stencil holder, etc., and the allied operating 25 parts of a typewriting machine of the well known Royal type:

Fig. 2, a right hand end view of the mechanism shown in Fig. 1:

Fig. 3, a vertical section on the line 3, 3, 30 of Fig. 1:

Fig. 4, a view showing a part of the ink ribbon controlling device: and

Fig. 5, a transverse section of the printing bed.

The ordinary parts of the Royal typewriter illustrated are the bed 5, or upper rail of the guide way, of the carriage, the lower rail 6 of the guide way; the end frames 7 of the carriage; the platen 8; the line spacing lever 9; and the connected 25 platen controlling devices 10.

The stencil holding frame guides 11 are secured by screws 12 to the upper rail 5 of the carriage guide way, their lower ends being offset to properly locate them and afford a free passage for the stencil frame, as shown in Fig. 1. The stencil frame comprises two flat side parts 13 connected together at their upper ends by a flat bar 14, and two flat springs 15 fastened to the lower ends of the side parts 13 and extending upwardly along their front faces, in such manner as to insure an adequate grip on the stencil and hold it in the frame. The 50 outer edges of the side parts 13 are formed

with rack teeth 16 which mesh into segmental gears 17 concentric with the platen and located at the ends of the printing bed to align with the rack teeth 16. Stencils adapted to be made on typewriting machines 60 usually consist of particularly prepared thin paper generally surrounded by a frame or border of stiffer material.

It is desirable to provide a means for limiting the upward and downward positions of the stencil frame. In upper position, the ends of the side parts 13 strike pins 18, projecting inwardly from the upper part of the guides 11, and are pressed backwardly, as shown at Fig. 2. This opens the 70 passage way between the side parts 13 and the springs 15 for the free insertion of a stencil blank in the stencil frame and the ready removal of the completed stencil therefrom. After a stencil has been put in 75 the frame 13, 14, 15, the platen is rotated and the stencil set down into printing position preferably by means of a hand lever 19 secured to the platen shaft, see Fig. 1 and the dotted lines Fig. 2. This hand lever 19 80 has an arm 20 projecting from its hub which contacts with an adjustable stop 21 secured to the end frame 7 of the carriage, the frame 13, 14, and stencil then being in lowermost position, see Fig. 3. After the stencil 85 is finished, or at any other time, it may be raised to its uppermost position by pushing the lever fully back. The arm 22, also projecting from the hub of the lever, then contacts with the stop 21, as shown in full 90 lines, Fig. 2.

The stencil characters are made clearly perceptible as they are impressed by the type over the ink ribbon 23, which covers the printing bed of the platen, by the ink therefrom showing through the punctures in the stencil made by the type. This ribbon is carried on a spool 24 whose shaft has bearings in plate frames 25, and these frames are secured to a bar 26 and extend in an angular rearward direction. The bar 26 extends between and is secured to the side frames 7 of the carriage. It is similar to, and may be used as, the paper pan carrying bar of the machine when fitted for ordinary typewriting. Between the ribbon spool 24 and the platen is a winding-up roller or spool 27 whose shaft or bearing studs rest in slotted holes 28 formed in the plates 25. This roller or spool 27 is rotated by a friction disk 27^a 101

22
 which contacts with the platen and so winds up the ribbon 23 which passes around the platen from the spool 24. A spring 35 held on the plate 25 acts on the shaft of spool 27 to press it toward the platen. Retrograde movement of the winding-up spool, when the platen is being set back by the hand lever 19, is prevented by the pawl 29 which is held against the ratchet 30 of the spool 27 by a spring 31. A small bell crank lever, pivoted to the frame 25, has one of its limbs 32 in front of the end of the shaft of the spool 27, its other limb 33 being located over the end of the pawl 29. This pawl 29 has an upwardly extending thumb piece 34 by means of which the pawl may be moved away from the ratchet 30 and so raise the limb 33 of the bell crank lever, thus causing the limb 32 to move the spool 27 away from the platen, as shown at Fig. 4. This will permit the ribbon from spool 27 to be rewound on the spool 24, by its manipulating knob 36.

It is advantageous in the application of typewriting machines to stencil making that the platen bed receiving the impact of the type be of a special character and readily renewable. To provide such a bed it is found that celluloid is a suitable material, and it may be applied to the active platen 37 as shown in Fig. 5. A sheet 38 of suitable material, as celluloid, of sufficient area to cover the printing part of the platen 37, is held in place by its upper and lower edges being slipped under cleats 39 secured to the platen. When worn such a sheet may be quickly replaced by a new one. The parts 8 of the platen shown in Fig. 1 may, of course, in this use of the typewriter be omitted as they then perform no function.

40 I claim:

1. In a stencil making device for typewriting machines, a rotatable platen, vertical guide frames rigidly secured to the bed of the carriage and located in front of the platen, a stencil holding frame fitted to slide between and in contact with the inner sides of the guide frames and an operating connection between the platen and stencil frame.
2. In a stencil making device for typewriting machines, a rotatable platen, a line spacing lever and its platen actuating connections, vertical guide frames rigidly secured to the bed of the carriage and located in front of the platen, a stencil holding frame located between and fitted to slide against the inner sides of the guide frames and an operating connection between the platen and stencil frame whereby the stencil frame is vertically moved when the platen is rotated by the line spacing lever.
3. In a stencil making device for typewriting machines, a rotatable platen, vertical guide frames rigidly secured to the bed of the carriage and located in front of the

65 platen, a stencil holding frame located between and fitted to slide against the inner sides of the guide frames, an operating connection between the platen and stencil frame and a hand lever secured to the platen 70 shaft and adapted to rock the platen to set the stencil holding frame in its upper and lower positions.

4. In a stencil making device for typewriting machines, a rotatable platen, vertical 75 guide frames secured to the bed of the carriage and located in front of the platen, a stencil holding frame fitted to slide against the inner sides of the guide frames, an operating connection between the platen 80 and stencil frame, a hand lever secured to the platen shaft and provided with two arms at its hub and a stop on the carriage frame against which the arms strike to limit the movement of the platen, said hand lever being adapted to rock the platen to set the stencil holding frame in its upper and lower positions.

5. In a stencil making device for typewriting machines, a rotatable platen, vertical 90 guide frames secured to the bed of the carriage and located in front of the platen, a stencil holding frame fitted to slide against the inner sides of the guide frames comprising two side parts, a connecting bar at their 95 upper ends, springs adjacent the front side of the side parts and attached to their lower ends and an operating connection between the platen and stencil frame.

6. In a stencil making device for typewriting machines, a rotatable platen, vertical 100 guide frames secured to the carriage and located in front of the platen, a stencil holding frame fitted to slide against the inner sides of the guide frames comprising two 105 side parts, a connecting bar at their upper ends, springs adjacent the front side of the side parts and attached to their lower ends, pins at the upper ends of the guide frames 110 against which the upper part of the stencil frame presses and moves away from the springs when it is in upper position, and an operating connection between the platen and stencil frame.

7. In a stencil making device for typewriting machines, a rotatable platen, vertical 115 guide frames secured to the bed of the carriage and located in front of the platen, a stencil holding frame comprising side pieces and a connecting top piece fitted to slide 120 between and in contact with the inner sides of the guide frames and having rack teeth formed in its side edges, and gears on the platen meshing into said rack teeth.

8. In a stencil making device for typewriting machines, a rotatable platen, vertical 125 guide frames secured to the carriage and located in front of the platen, a stencil holding frame fitted to slide against the inner sides of the guide frames and having rack 130

- teeth formed in its side edges, gears on the platen meshing into said rack teeth, a hand lever secured to the platen shaft and provided with two arms at its hub, and an adjustable stop on the carriage frame against which the arms contact said hand lever being adapted to rock the platen to set the stencil holding frame in its upper and lower positions. 5
10. A typewriter stencil-making device, comprising a rotary platen, a carriage in which the platen is supported, an adjustable stencil holder located in front of the platen and supported by said carriage, a stencil carried by the holder, and an ink carrier supported independently of the platen and located between the stencil and the platen. 15
10. A typewriter stencil-making device, comprising a rotary platen, a carriage in which the platen is supported, an adjustable stencil holder located in front of the platen, a stencil carried by the holder, an ink carrier located between the stencil and the platen, and means operable independently 20 of the movement of the platen for moving the ink carrier relatively to the line of print.
11. The combination with a rotary platen, of a stencil holder associated with the platen, means for moving the stencil holder relatively to the line of print, a stencil carried by the holder, an ink-ribbon interposed between the stencil and the platen, a spool on which the ribbon is wound and from which it is drawn around the platen and between 30 the platen and the stencil, a winding-up roll for the ribbon, and means yieldingly connecting said winding-up roll with the platen whereby the former is driven by the latter. 35
12. The combination with a rotary platen, of a stencil holder associated with the platen, means for moving the stencil holder relatively to the line of print, a stencil carried by the holder, an ink-ribbon interposed between the stencil and the platen, a spool on 40 which the ribbon is wound and from which it is drawn around the platen and between the platen and the stencil, a winding-up roll for the ribbon, means connecting said winding-up roll with the platen whereby the former is driven by the latter, and means for connecting and disconnecting the winding-up roll and platen. 45
13. The combination of a rotary platen, a carriage on which it is mounted, stencil 50 guide frames secured to the carriage, a sten-
- cil holder adjustably mounted in said guide frames, an ink-ribbon interposed between the stencil-holding frame and the platen, a ribbon spool from which the ribbon is drawn, a winding-up spool for the ribbon, friction 60 gearing connecting the winding-up spool with the platen, means for moving said friction gearing in and out of operative connection with the platen, and detent mechanism for said winding-up spool. 65
14. The combination of a rotary platen, the carriage in which it is mounted, guide frames rigidly secured to the carriage, a stencil holder arranged tangentially to the platen and vertically adjustable relatively 70 thereto, and springs interposed between the guide frames and the stencil-holding frame and attached to the latter for holding the stencil in place in its frame. 75
15. The combination of a rotary platen, its carriage, a stencil guide frame attached centrally thereto, a stencil-holding frame mounted to slide on said guide frame, means for moving said stencil-holding frame, and means carried by the guide frame for moving the stencil-holding frame rearwardly 80 away from said guide frame at its upper end as the stencil-holding frame rises on the guide frame. 85
16. The combination of a rotary platen, a carriage in which it is mounted, a stencil guide frame attached to the carriage, stencil-holding springs carried thereby, means for moving the stencil-holding frame in its guide frame, and means carried by the guide frame 90 for moving the stencil-holding frame rearwardly as said frame is moved in its guide frame. 95
17. A typewriter stencil making device, comprising a shifting rotary platen provided with a removable impact surface, a carriage in which the platen is supported, a stencil-holder located in front of the platen, an ink carrier located between the stencil and the impact surface of the platen, automatically controlled means for moving said ink carrier in one direction, and independently operable means for moving the ink carrier in the other direction. 100
- In testimony whereof, I have hereunto 105 subscribed my name.
